UNITED STATES PATENT OFFICE

ELSIE KLAGGES, OF GLENDALE, NEW YORK

PENCIL

Application filed February 21, 1928. Serial No. 255,901.

This invention relates particularly to pencils of the lead projecting, retracting and expelling class.

Special objects of the invention are to provide with a pencil of this class, an eraser which will be automatically projected or uncovered before the lead is projected for use and will be retracted or covered before the lead is withdrawn after use.

10 Further objects of the invention are to provide eraser mechanism of entirely practical, convenient and satisfactory construction and operation and which can be readily combined with pencil structures of the general 15 type now in common use.

The foregoing and other desirable objects are attained by certain novel features of construction, combinations and relations of parts as hereinafter described and as illustrated 20 in the accompanying drawing.

The drawing illustrates one of the practical embodiments of the invention, it being understood that the structure may vary without departure from the true spirit and broad 25 scope of the invention.

Figure 1 is a longitudinal vertical sectional view of a practical embodiment of the invention, showing both the lead and the eraser projected, ready for use.

30 Figure 2 is an enlarged broken sectional view showing the construction at the eraser end of the pencil.

Figure 3 is a broken view partly in elevation showing the eraser withdrawn into the 35 operating sleeve on the end of the pencil.

Figure 4 is a broken part sectional view illustrating a modified form of the eraser operating mechanism.

40 Figure 5 is an end view of the parts shown in Figure 4.

In Figure 1, the pencil is shown as having a tubular body 6 of suitable size and shape and as having guided within the tip of the same, a sliding carrier 7 for the lead 8. This carrier is indicated as operated in the usual way by a lug 9 engaging in the groove of a helically twisted operating member 10 and the pin which ejects the lead in the final movement is shown as having a similar lug 11

working in the same groove, as customary in pencils of this type.

Instead of turning the screw feeding member 10 directly, in the usual way, a certain amount of lost motion is introduced in the 55 actuating connections and this lost motion period is utilized to effect the actuation of the eraser.

The eraser is shown at 12, seated in the outer end of a tube 13 which is secured at the inner end to a smaller sleeve 14 surrounding the screw feed 10 and carrying a pin 15 working in the groove of the screw feed.

Surrounding the eraser sleeve 13 is a finger piece 16 in the form of a suitably knurled 65 collar or the like, rotatably held on the end of the pencil barrel and having a pin 17 engaging in a longitudinally extending slot 18 in the eraser sleeve.

The finger piece 16 is shown as rotatably mounted on the end of the pencil barrel by means of a bearing sleeve 19 forced into the end of the body piece 6 and having a flange 20 at its outer end extending in back of a bushing 21 fixedly seated in the inner end of the finger piece, said bushing having a rotating fit on the bearing sleeve 19 and the eraser carrying sleeve 13 having a rotating fit within the bearing sleeve. The parts may be assembled by forcibly seating the bushing 21 in the finger sleeve 16 over the bearing sleeve 19, thus locking these parts together and then forcing the bearing sleeve into frictionally held relation in the end of the pencil barrel.

With this construction, it will be apparent that as the finger piece is turned, the eraser sleeve also will be rotated and the first effect of this will be to either retract or project the eraser as the pin 15 at the inner end of the 90 eraser sleeve travels in the groove of the feed screw, the feed screw remaining stationary during such operation, being held so by its frictional mounting in the barrel.

In Figures 1 and 2, it will be evident that 95 by rotating the finger piece left handedly, the pin 15 will ride forwardly in the groove of the feed screw, thereby withdrawing the eraser sleeve and carrying the eraser inwardly into the actuating sleeve 16. This movement will 100

continue until the outer end of the slot 18 engages the pin 17 or until the inner end of the guide sleeve 14 surrounding the feed screw contacts with the end of the sleeve 22 surrounding the forward end of the feed screw. In either event, the retracting movement of the eraser sleeve is arrested and the further rotation of the finger piece thereby becomes effective through the pin 15 to turn the feed screw and retract the lead carrier.

In the reverse or right handed rotation of the finger piece, with the eraser and lead carrier both retracted, it will be seen that the first effect of the rotation will be for the eraser sleeve to screw itself outwardly over the feed screw and that when the end of this movement is reached, that is, when the pin 15 contacts the stop 23 on the feed screw or the pin 17 is engaged by the inner end of slot 18, rotation will be imparted to the feed screw and the lead carrier will be thereby projected.

In the species illustrated in Figs. 4 and 5 the eraser 12 may be mounted in the outer cylindrical end of a sleeve 22', the inner end of which is reduced and squared to have a sliding fit over the square member 23' rigidly fastened to the operating member 10. A pin 24 projects from the sleeve 22' and engages in a helical groove 25 formed in the inner wall of the finger piece 26. For convenience in manufacture the finger piece 26 is shown as composed of an inner collar 27, having groove 25 cut through its wall, and an outer collar 28 longer than the inner collar. The finger piece 26 is rotatably attached to the body 6 in the same manner as the finger piece of Figs. 1 and 2.

With the parts in the relation indicated in Fig. 4 both eraser and lead are in retracted positions. Upon rotating the finger piece right handedly the groove 25 will push the pin 24 toward the left, thereby moving the sleeve 22' toward the left and causing it to slide over the nut 23, simultaneously projecting the eraser. When the pin 24 reaches the end of slot 25, further rotation of the finger piece will turn the operating member 10 through the square member 23' and cause projection of the lead. Operating the finger piece in the reverse direction will first retract the eraser and then the lead.

I claim:

1. A pencil comprising a case, an operating member revolvably mounted at one end thereof, a lead carrier projectible at the other end of the case, operating means for the lead carrier including a helical member and a lost motion device, an eraser carrier arranged to project an eraser at the end of the case adjacent the operating member, a combined rotary and slidible connection between the operating member and eraser carrier, and a connection between the eraser carrier and the lead carrier operating means through the lost

motion device, whereby when the operating member is rotated in one direction the eraser is projected and thereafter the lead is projected; and in the other direction, the lead is first retracted and thereafter the eraser is retracted.

2. A pencil comprising a case, an operating member revolvably mounted at one end thereof, a lead carrier projectible at the other end of the case, operating means for the lead carrier including a helical member and a lost motion device, an eraser sleeve arranged to project an eraser at the end of the case adjacent the operating member, a pin and slot connection between the operating member and eraser carrier, and a connection between the eraser carrier and the lead carrier operating means through the lost motion device, whereby when the operating member is rotated in one direction the eraser is projected and thereafter the lead is projected; and in the other direction, the lead is first retracted and thereafter the eraser is retracted.

In testimony whereof I affix my signature.

ELSIE KLAGGES.
